FUEL INJECTION PUMP

Desire J. Deschamps, Rutherford, N. J., assignor to Deschamps Fuel Injection Corporation, New York, N. Y., a corporation of New York

Application March 5, 1947, Serial No. 732,491

11 Claims. (Cl. 103—37)

1

This invention relates to an improved high pressure fuel injection pump for injecting liquid fuel into the cylinders of an internal combustion engine, particularly high power multi-cylinder aircraft engines. More specifically, the invention relates to such a pump including a plurality of pumping units each operative to deliver liquid fuel selectively to more than one cylinder of an engine.

It has been the practice in the past to provide fuel injection pumps with as many pumping units as there are cylinders on the engine, each pump plunger, also called pumping unit, delivering an accurately metered amount of fuel, with the proper timing, to its respective engine cylinder.

The steadily increasing speed and size of airplanes requires engines of greater power output and, as there exists a practical limit as to the power output that can be obtained from a single engine cylinder, the solution has been to increase the number of cylinders rather than the cylinder size. Whereas nine cylinders represented the largest number of cylinders used in engines up until recently, engines of 14, 16, 18, 24, 28, 36 and even 42 cylinders are now in use or are under development.

For practical considerations the present fuel injection pumps used on aircraft engines have been limited to not more than 14 plungers (pumping units), and only a few experimental fuel injection pumps have been built with 18 plungers. This means that engines of more than 14 cylinders have been equipped with more than one fuel injection pump; for instance, two 9-plunger pumps for an 18-cylinder engine, two 12-plunger pumps for a 24-cylinder engine, two 14-plunger pumps for a 28-cylinder engine, etc.

The installation of several fuel injection pumps on a single engine creates many problems. It is difficult to find room on an engine for installing this number of pumps and to provide driving means therefor. As is well known, mounting pads and drive gearing have to be provided on an engine for various accessories leaving little available space for additional pumps.

Not only is the mechanical problem complicated by the use of several pumps, but also the weight of the engine is appreciably increased. Another serious problem is that the necessary added gears, couplings and bearings increase the risk of mechanical failure and complicate the servicing and maintenance problems. Furthermore, difficulty is experienced in connecting the capacity control of each pump to a common fuel control unit, and to obtain and maintain in service the accurate calibration of the fuel delivery from each pump, as is necessary in modern high-power output engines.

Broadly the main object of this invention is to provide a fuel injection pump of which the plungers do "double duty," meaning that each

2

pumping unit, instead of delivering fuel to only one engine cylinder, delivers an accurately metered and timed injection to two or more engine cylinders of which the power strokes are properly spaced. For instance, with a 9-plunger pump of the invention type, it is possible to supply fuel to the cylinders of an 18-cylinder engine, replacing the two 9-plunger pumps now considered necessary. This results in a simplification of the engine, as only one pump mounting pad and one pump drive have to be provided, all difficulties in properly synchronizing two separate pumps are removed, the new pump is lighter in weight and lower in cost than the two pumps it replaces, and its size is not much larger than the present 9-plunger pump.

Although the pump, which is the object of this invention, replaces an 18-plunger pump, its production is far from offering the problems of the latter, and the new pump is not expected to cost more than about 65% of the total cost of the two pumps it replaces.

It is among the objects of the present invention to provide a fuel injection pump including pumping units capable of selectively delivering fuel under pressure to more than one engine cylinder; to provide such a pump including a rotating plunger of an improved design, acting not only as a pumping and metering unit but also as a distributor of the fuel to more than one engine cylinder; to provide such a pump of which each pumping unit includes a rotating plunger in a ported bushing effective to distribute fuel selectively to different ports of the bushing and in which the relation between the plunger distributing means and the ports of the bushing is not critical due to the use of means independent of the plunger rotation to accurately time and meter the amount of fuel being delivered at each injection.

A further object is to provide for such a pumping unit having a fuel compression chamber and a fuel distributing means, and a check or delivery valve arrangement disposed between such chambers and the distributing means to prevent back flow of fuel during the suction stroke to affect the accurate metering of the fuel delivery.

Another object is to provide accurate means for effecting the fine adjustment, as needed, of the fuel delivery from each individual pumping unit to equalize the pumping unit outputs; only a very minute variation in output being allowed from each plunger to another.

Still another object of this invention is to provide a pump having a housing divided into two main compartments, a fuel compartment in which are installed the plunger bushings and the fuel output controlling means and a drive compartment containing the pump shaft, bearings, plunger-actuating cam and the plunger tappets; to provide for pump plungers extending into both compartments and effective seal-

ing means between the fuel compartment, drive compartment, and plunger to avoid the loss of lubricating oil into the fuel or the seepage of fuel into the drive compartment; to provide such a pump including a plurality of pumping units operated by tappets each having a roller engaged by a rotatable actuating cam driven from the engine; and to provide such a pump including guiding means for maintaining the tappets accurately aligned with the actuating cam.

An important feature of the pump is the utilization of means independent of the plunger rotation to control the injection timing. The closing of the fuel inlet port to the plunger and the opening of the spill port, which both govern the length, volume and timing of the injection are controlled by the reciprocating motion of the plunger and not by its rotating motion.

Another important feature is the avoidance of both mechanical and hydraulic side thrust on the plunger, so that the plunger may "float" in its bushing. This has been found to be extremely important to avoid rapid wear and even "sticking" of the plunger when pumping fuel with poor lubricating properties, such as gasoline.

Mechanical side thrust on the plunger is avoided by the use of a tappet between the plunger and the actuating cam. To avoid side thrust due to hydraulic pressure acting through the ports against the plunger, use is made of diametrically opposed ports in the bushing and diametrically opposed distributing grooves in the plunger, this arrangement insuring perfect hydraulic balance.

The rotating motion of the plunger in addition to its reciprocating motion has the added advantage of substantially reducing the danger of "sticking" plungers, as any foreign matter which accidentally may become lodged between the plungers and the walls of the plunger bushings is kept moving and works itself free between the plunger bearing surfaces in the bushings.

Other features of this pump are covered by the following applications copending herewith and assigned to the same assignee as the present application: Application Serial No. 503,470, filed September 23, 1943, by Desire J. Deschamps and Douglas C. Clarke, now Patent No. 2,519,893, issued August 22, 1950; Application Serial No. 515,696, filed December 27, 1943 by Desire J. Deschamps, Douglas C. Clarke and Frank E. Ferguson, now Patent No. 2,436,797, issued March 2, 1948; and Application Serial No. 591,914, filed May 4, 1945 by Desire J. Deschamps, now Patent No. 2,531,202, issued November 21, 1950.

As said, the description which follows is of a 9-plunger, 18-outlet pump, arranged to be driven at one half crankshaft speed for application to a four-cycle 18-cylinder engine, and the porting control of the plunger has been provided for fixed timing of the beginning of the injection period and variable timing of the ending thereof.

Only minor changes, as will be explained at the end of the description, make this pump applicable for other methods of operation, such as running the pump at crank shaft speed on a four-cycle engine. Another variation is to provide for a fixed timing of the ending of the injection and variable timing of the beginning of the injection with respect to the plunger reciprocating motion.

In general, the invention provides a novel, compact fuel injection pump capable of deliv-

ering fuel to a number of engine cylinders which number is a multiple of the number of pumping units incorporated in the pump, and which pump is simple in operation, easy to service and adjust, and capable of reliable operation.

The other novel advantages, features and characteristics of this pump will be apparent to anyone familiar with the art from the following detailed description and the accompanying drawings. In the drawings:

Fig. 1 is a longitudinal sectional view of a pump constructed according to the present invention, taken on the line 1—1 of Fig. 10.

Fig. 2 is an enlarged sectional elevation view of one of the pumping units of the pump.

Fig. 2A is a left-end elevation view of Fig. 2.

Figs. 15 through 17 are views similar to Fig. 14, illustrating other positions of the pumping unit during a stroke. Fig. 15 shows the plunger at the beginning of injection, Fig. 16 at the ending of injection, and Fig. 17 at the ending of the compression stroke.

Fig. 18 is a sectional perspective view showing the plunger rotated 90° from the position of Fig. 15 and ready to start delivery of fuel through a different set of fuel outlet ports.

Fig. 19 is a diametrical sectional view on the line 19—19 of Fig. 14.

Figs. 20 through 23 are views similar to Fig. 19, but corresponding to Figs. 15 through 18, respectively.

Fig. 24 is a diagrammatical, diametrical sectional view illustrating the hydraulically balanced fuel delivery arrangement of a pumping unit in a position of the plunger corresponding to Figs. 15 and 20.

Fig. 25 is a view similar to Fig. 24, showing the plunger in a position corresponding to Figs. 18 and 23.

Generally speaking, the high speed fuel pump of the present invention includes a number of successively operable pumping units, each arranged to deliver fuel to more than one cylinder of an internal combustion engine. Each pumping unit includes a cylinder or bushing having

separate sets of ports each connectible with an individual engine cylinder, and a plunger reciprocable and rotatable with respect thereto both to inject fuel into the engine cylinders and to distribute the fuel, on successive strokes, to different cylinders. The injection or delivery of fuel, and the timing of injection, is controlled by the reciprocation of the plunger. The distribution of fuel to different cylinders is effected by rotation of the plungers.

Rotatable face cam means, operated in timed relation with the engine crank-shaft, engage tappet means to reciprocate the plungers in succession, and means are provided to maintain the tappets accurately aligned with the face cam means. Gearing operated by the face cam means rotates the plungers between each stroke, to deliver fuel to different cylinders on successive strokes.

Other features of the invention comprise novel arrangement for mechanically and hydraulically balancing the plungers to eliminate side-thrust thereon and assure a substantially floating reciprocation of the plungers. Also, novel sealing means are provided between the fuel and driving compartments of the pump to prevent leakage of lubricating oil into the fuel compartment, and dilution of the lubricating oil in the driving compartment by fuel leakage from the fuel compartment.

The rotating plunger type of pumping unit of the invention can be used with any desired arrangement and number of engine cylinders, and with either two or four-cycle engines.

For example, if the operating cam has two lobes spaced 180° and proper gearing is provided to rotate the plungers at one-half the angular velocity of the cam, each pumping unit may supply fuel alternately to two cylinders of a four-cycle engine. In such case, the working strokes of the two cylinders supplied from the same pumping unit must be spaced 360° from each other, and the cam is rotated at one-half of the engine crank-shaft speed.

As an alternative to this arrangement, a single lobe cam operated at crank-shaft speed, with the plungers rotated at one-quarter crank-shaft speed can likewise effect delivery of fuel to two cylinders of a four-cycle engine from each pumping unit. Also, this can be accomplished by a four-lobe cam operated at one-quarter crank-shaft speed, with the pumping plungers likewise rotated at one-quarter crank-shaft speed.

The pump may also be used with each individual pumping unit supplying fuel alternately to two cylinders of a two-cycle engine, with the working strokes of the cylinders spaced 180°. This can be accomplished with a two-lobe cam rotating at crank-shaft speed, and the plungers rotating at one-half crank-shaft speed. Also, a single-lobe cam can be used operating at twice the crank-shaft speed or a four-lobe cam operating at one-half the crank-shaft speed. In both cases, the plungers are rotated at one-half the crank-shaft speed.

Another possible arrangement is for each pumping unit to supply fuel to a single cylinder of a two-cycle engine, using two spray nozzles to introduce fuel to the cylinder. The rotating plungers will deliver fuel alternately to each nozzle on alternate working strokes of the cylinder. This can be accomplished by a two-lobe cam rotating at one-half crank-shaft speed, with the plungers rotating at one-quarter crank-shaft speed. Also, a single-lobe cam rotating at crank-

shaft speed can be used with the plungers rotating at one-quarter crank-shaft speed.

In all of the above arrangements, the angular velocity of the plungers is equal to one-quarter the angular velocity of the cam multiplied by the number of cam impulses per cam revolution.

In the illustrated pump, nine pumping units are provided, equally spaced about the circumference of a circle and equi-distant from the axis of the pump drive-shaft. The pumping units are disposed with their axes of reciprocation parallel to the pump drive-shaft. This type of pump is usually referred to as a "barrel" pump. However, it should be noted that the illustrated embodiment is typical only, and that the principles of the invention are applicable equally to any fuel injection pump with a different number of pumping units, or with the units arranged in a different relation to the pump driving means.

Referring more particularly to the drawings, the general arrangement of the pump will be best understood from Figs. 1 and 2. As shown, the pump includes a fuel compartment 31 and a drive compartment comprising sections 32 and 33. These compartments are formed by the assembly of several elements constituting the pump housing.

At the end of the pump nearest the engine, hereinafter referred to as the inner end of the pump, a pump head 34 is provided, closed by a plate 35 and formed with a mounting flange 36 by means of which the pump is attached to the engine. Head 34 is the supporting member for plunger-bushing assemblies 43, forming the cylinders of pumping units 30.

Secured to head 34 is a central housing member 37 having a fuel inlet port 38 and formed with a transverse flange or diaphragm 39 separating the fuel compartment 31 from the drive compartment 32, 33. Diaphragm 39 acts as a support for the sealing means between the two compartments and also for plungers 90 of pumping units 30, and elements associated with the plungers.

At its outer end, housing 37 has attached thereto a tappet housing 40 which supports tappets 105 and the inner bearing 133 of rotatable face cam 112. Housing 40 has a flange 41 bolted between the outer end of housing 37 and a flange formed on a cam housing 42. Cam housing 42 supports the outer bearing 134 of cam 112, and acts as a closure for the outer end of the pump.

Fuel compartment 31 is formed in housing 37 between diaphragm 39 and head 34. The drive compartment sections 32, 33, are closed by diaphragm 39 and cam housing 42. The described pump housing elements are secured together in any suitable manner by two series of studs, screws or bolts, engaged in apertures provided in the joining flanges of the several housing sections.

As stated, the pump includes a number of pumping units 30, nine in the present embodiment. Each pumping unit includes a bushing assembly 43, a delivery or check valve 72, a plunger 90, an output control sleeve assembly 170, and a plunger driving mechanism including a geared sleeve 136 and a tappet mechanism 105. Geared sleeves 136, in a manner to be described, effect rotary motion of plungers 90. Similarly, tappet mechanisms 105, as will be described, effect reciprocating motion of plungers 90. Specifically, pumping units 30 are actuated by cooperation between tappets 105 and a face cam 112 driven through a quill shaft 130 at a proper speed ratio with the engine crank-shaft. Also as will

be described, the pump plungers 90 are rotated by gearing interconnecting cam 112 and sleeves 136.

A series of apertures equal in number to the number of pumping units are arranged in equi-spaced relation around the circumference of a circle centering on quill shaft 138 and extending through pump head 34 parallel to the axis of the quill shaft. These apertures receive bushing assemblies 43 which, as shown more particularly in Figs. 6 and 7, comprise an inner bushing 44 and an outer sealing sleeve 45.

Bushing 44 is formed with a shoulder or rib 46 which locates the bushing by engagement in a recess in pump head 34. A collar 47 extends forwardly from shoulder 46 and cooperates with a recess in head 34 to receive a packing ring 48 made of a suitable resilient material. The dimensions of the packing ring recess are such that the ring 48 is slightly squeezed and deformed when holding screws 49 are tightened to secure plate 35 to head 34.

Bore 50 in bushing 44 is machined to such dimensions as to give the proper sliding fit between the bore and pump plunger 90. The outer end of bore 50 forms a sharp corner edge 51 with the end of bushing 44. The inner end of bore 50 is enlarged to form a compression space 52 above the inner end of plunger 90. Compression space 52 communicates with an external angular groove 54 in bushing 44 by means of one or more drilled channels 53.

Outwardly from groove 54, a set of four equally spaced apertures 58 are drilled radially through bushing 44, connecting bore 50 with a second external annular groove 55. Substantially at its central portion, a third annular groove 56 and, close to its outer end, a fourth annular groove 57 are formed externally in bushing 44. Halfway between grooves 56 and 57, a second set of four equally spaced apertures are drilled radially through bushing 44.

Two diametrically opposed apertures 59 of this second set each open into a longitudinal groove 60 on the external surface of bushing 44, communicating with groove 56. The two other diametrically opposed apertures 61 of the second set each communicate with a longitudinally extending external groove 62. Grooves 62 communicate, at their outer ends, with external annular groove 57.

Outer sleeve 45 is assembled over, and preferably shrunk on bushing 44. Sleeve 45 seals grooves 54, 55, 56, 57, 60 and 62, thus forming a system of fuel passages the purpose of which will be explained when the operation of the pump is described. A series of four holes, 63, 64, 65 and 66 are drilled through sleeve 45 and communicate respectively with grooves 54, 55, 56 and 57 in bushing 44.

Referring more particularly to Fig. 2, bushing assembly 43 is installed in its aperture in head 34 in such a manner that holes 63, 64, 65 and 66 in sleeve 45 register with certain respective fuel channels formed in pump head 34. Holes 63 and 64 register, respectively, with drilled passages 67 and 68 closed at their outer ends by suitable means, such as plugs 69. A passage 70 interconnects passages 67 and 68. When no fuel is flowing through passage 70, the passage is closed by a check or delivery valve 72 installed in a bore in head 34.

A spring 76 biases valve 72 against valve seat 71 formed by the intersection of passages 70 and 68. In the particular arrangement shown in the

drawings, spring 76 is centered in a cap 77 closing the housing of valve 72 and held in place by a set screw 78. Valve 72 has a reduced portion 79 of smaller diameter than the valve bore in order to form a substantially annular chamber 78 adjacent seat 71 to facilitate the flow of fuel. This reduced portion 79 is shaped to form a tight sealing fit with valve seat 71. In the illustrated embodiment, valve 72 has a spherical end 74 seating against seat 71, but it is within the contemplation of the invention to use a flat or angular valve seat and valve end. Holes 65 and 66 in sleeve 45 are the exits for fuel passing toward the engine cylinder.

Again referring to Fig. 2, the eighteen screws passing through holes 80 in mounting flange 38 not only secure the pump to the engine but also act as fuel fittings for the fuel lines carrying the fuel to the engine cylinders. Hole 68 registers with a drilled passage 85 opening into a second passage 86 closed at its outer end by a plug 87. Channel 86 communicates with a channel 88 terminating in an enlargement 89 of bolt hole 80. One or more cross holes 83 are drilled through 25 the stem or bolt 82, intersecting an axial passage 84 therein for the flow of fuel to an appropriate fitting for connecting the fuel line to the engine cylinder. As the details of such connection form no part of the present invention, they 30 have not been shown in the drawing.

In Fig. 6, the second fuel outlet hole 65 is illustrated as being in the same radial plane as hole 66. Actually, hole 65 is in a different radial plane than hole 66, as exemplified by the dotted 35 line illustration in Fig. 2. Outlet holes 65 and 66 each communicate with a different bolt 82, and these bolts are located 20° apart on the mounting flange. Through its passage 89, outlet hole 65 communicates with a bolt 82 in the same 40 manner as does hole 66. However, this second bolt 82 is located in a plane different from that of bolt 82 shown in Fig. 2 of the drawing.

Plunger 90 is a generally cylindrical member 45 which, in the invention pump, performs three functions in cooperation with bushing assembly 43 and other coating parts to form the pumping units 30. The reciprocating motion of the plunger not only draws in fuel and compresses it, but also controls the timing and volume of 50 the injection through the plunger inlet and spill ports. Furthermore, the rotating motion of the plunger controls the distribution of the fuel to the proper fuel outlet.

The construction of plunger 90 is more clearly 55 illustrated in Figs. 3, 4 and 5. As therein shown, the inner end, or the end nearest the engine, is formed with a wide external annular groove 91 forming a fuel chamber. A pair of diametrically opposed longitudinal grooves 92 communicate 60 with groove 91. The circumferential width of these grooves covers an arc of sufficient length to insure communication, at the proper time in the rotation of the plunger, with either set of outlet holes 59 or 61 in bushing 44. Furthermore, 65 grooves 92 are of sufficient length to insure free and unrestricted passage of fuel from groove 91 to outlet holes 59 or 61 during the maximum duration of the injection period.

The inner end of the plunger, as just described, 70 has the function of distributing the fuel alternately to different outlets through the rotation of the plunger. The control of the length and volume of the injection is performed by a section of the plunger disposed outwardly, that is 75 away from the engine, from groove 92.

This latter control comprises a pair of annular external grooves 93 and 94 which cooperate respectively with the edge 51 of bushing 44 and the inner edge of sleeve 170 to define and control the opening and closing of the fuel inlet and spill ports. Cross holes 95 connect grooves 93 and 94 to an axial passage 96 in plunger 90. The two grooves are thus put into communication with compression space 52 at the inner end of bushing 44.

In the intermediate portion of plunger 90 are two external annular grooves 97 and 98. These are relatively narrow grooves which receive packing rings 99 cooperating with sleeve 136 to provide an effective seal between fuel compartment 31 and drive compartment 32. The part of the plunger outwardly of groove 98 is of smaller diameter and carries driving lugs 100 registering with two diametrically opposed slots 141 in geared sleeve 136. The outer end of the plunger terminates in a button 101 having a convex surface 102 to obtain a point contact with a hardened thrust disk 103 (Fig. 2). Button 101 also acts as a retaining shoulder for a slotted spring washer 104.

The tappet assemblies 105 are slidably mounted in cylindrical apertures provided in tappet housing 40. These apertures are parallel to the pump axis, are equally spaced around the circumference of a circle having a center on the pump axis, and are each aligned with one of the pumping unit apertures in head 34. Each tappet body 106 is cylindrical in shape, with the inner end 107 being hollow to form a sleeve. Sleeve 107 has the function of increasing the bearing length of the tappet without an appreciable increase in weight. The outer part of the tappet body is slotted to receive a roller 108 having a "floating" bearing bushing 109. Roller 108 is held in tappet body 106 by a pin 110 having convex ends. Pin 110 "floats" freely in its bore in the tappet but cannot move axially because, over the entire length of the tappet stroke, pin 110 is confined in the tappet guiding passage in housing 40.

The outer end of the tappet forms a skirt 111 partly cut away to give the tappet free movement past cam 112 during the full stroke of the tappet. Referring to Fig. 2A, it will be seen that the remaining segment of skirt 111 fits against the periphery of cam 112. This prevents rotation of the tappet and keeps roller 108 properly aligned with the cam and the axis of pin 110 directed toward the center of the cam rotation. This arrangement is of great importance in insuring proper rolling contact between cam 112 and roller 108.

In the illustrated pump embodiment, roller 108 is a tapered roller and a tapered rim 115 is formed on cam 112. The taper is at the proper angle to insure rolling contact over the whole width of the surfaces in contact. An alternative construction is to use a roller with a crowned rim working against a taper on a flat-faced cam. However, this would give only point contact between the roller and cam, instead of the line contact with the illustrated arrangement.

Cam 112 is a face cam formed by a shaft 113 supported in bearings 133 and 134, a disk 114 and a rim 115 (Figs. 1 and 12). Bearing 134 absorbs the thrust load due to the plunger springs 142 and the hydraulic pressure on the plungers. Inwardly of bearing 133, a 24-tooth gear 125, called a sun gear, is formed on shaft 113. Splines 126 on the inner end of shaft 113 engage co-

operating splines in drive shaft 130 which is of the type usually called a quill shaft.

This type of drive allows for a certain amount of misalignment between the pump and the engine drive, and the size and proportions of quill shaft 130 can be selected to absorb the torsional vibration in the engine drive. To prevent shaft 130 from "floating," it is held in engagement with cam shaft 113 by means of a spring lock. 10 This lock comprises two small balls 128 biased apart by spring 129 and engaging an internal annular groove 131 in the tubular coupling end of shaft 130. The innermost end of shaft 130 has a splined coupling of the required dimensions to engage the pump driving means of the engine.

In the illustrated embodiment, cam 112 is a two-lobe cam of which the design is best illustrated by the development of the cam surface shown in Fig. 13. Referring to this figure, the tops or noses of the two lobes are indicated at 116 and 117 as spaced 180° apart. On either side of each lobe are the cam flanks 118 and 119 connecting the tops to the lower or level part 25 120 of the cam. The flanks are straight and symmetrical and are joined to flat part 120 and noses 116, 117 by means of curves 121 and 123, respectively.

The vertical distance A between part 120 and 30 top 117 defines the stroke of plunger 90. In the illustrated embodiment, this distance is 0.5625". When roller 108 moves up the cam during the working stroke of the plunger, the distance from point 120 to point 122, referred to as B, represents the height of the fuel inlet port. In the present case, this distance is 0.1907". At point 122, the inlet port closes. The distance represented by the distance C is the maximum length or effective delivery stroke of the plunger. This distance may be, for example, 0.300". At the upper end of dimension C, the spill port opens relieving the pressure existing in compression space 52 at the inner end of bushing 44. The two flanks of each cam lobe could, of course, be made asymmetric, and the angle changed dependent upon the length of injection of other special injection characteristics to be obtained.

Diaphragm 39 is formed with a series of apertures each perfectly aligned with the corresponding aperture in head 34 and tappet housing 40. Bushings 135 are permanently inserted in these apertures and project beyond the inner face of diaphragm 39. Sleeves 136 are assembled in bushings 135 with the proper running fit to allow 55 free rotation of each sleeve 136 in its bushing 135.

An annular groove is formed in the outer wall of sleeves 136 to receive a packing ring 137. Each sleeve 136 carries, intermediate its ends, 40-tooth gear 138, and is formed with a shoulder 139 by means of which it is held against the flange of bushing 135 under the pressure of spring 142.

The outer end of sleeve 136 is a sleeve-like extension 140 having a pair of opposed slots 141 receiving driving lugs 100 of plunger 90. Slots 141 are sufficiently long to provide for unrestricted reciprocating movement of plunger 90 in sleeve 136, while providing for free rotation of the plunger and sleeve as a unit.

70 The bore of sleeve 136 is sufficiently large to allow an appreciable amount of clearance with plunger 90, to provide for possible misalignment of bushings 135 with the corresponding apertures in head 34 and tappet housing 40, or for lack of 75 concentricity of the parts. It will be noted that

the seal between the fuel and drive compartments is not dependent upon a close sliding fit of plunger 90 in bushing 136 but that two special packing rings 98 are provided for sealing purposes.

In previous pump designs, the oil under pressure lubricating these moving parts insured a fairly satisfactory seal while the pump was in motion. However, with the engine at rest, the fuel from the fuel compartment slowly dissolved the oil from between the bearing surfaces and finally seeped into the drive compartment and from there through the pump drain into the engine sump where it diluted the oil. In the present design, such seepage is avoided by packing rings 98 and 187.

Cam 112 has two lobes, causing each plunger 90 to make two full strokes for one revolution of the cam, successive strokes being spaced 180°. In order to align distributing grooves 92 of plunger 90 with the proper outlet ports to deliver fuel to alternate cylinders on each stroke, plungers 90 must rotate 90° between impulses. In effect, the plungers must rotate at one-half the cam velocity. This is obtained by the use of gearing, having the proper reduction ratio, between cam shaft 113 and sleeve 136.

In the center of the pump is a sleeve member 145 pressed permanently into place in a central aperture in diaphragm 38. The outer end of sleeve 145 is enlarged to abut against a thrust washer 147 engaging diaphragm 38. The portion of sleeve 145 projecting through diaphragm 38 is reduced in diameter at 148 to form a shoulder abutting pump head 34. Reduced portion 148 has a sliding fit in a central aperture of head 34, and a leak-proof joint is obtained by two packing rings 150. Any longitudinal motion of sleeve 145 is prevented by its pressed fit in diaphragm 38 and by retaining ring 160.

The radially outer surface of sleeve 145 is plated with silver, or other suitable bearing material, to provide a bearing surface for a ring gear 161. A gear cage 162 is secured against sleeve portion 145 by means of screws 262. Cage 162 supports a series of satellite gears 163 each rotatably mounted on a pin 164. In the illustrated embodiment there are three such satellite gears but a different number might be used depending on the load involved.

Gear 125 on cam shaft 113 meshes with a relatively large 28-tooth gear on satellite 163. A relatively small 20-tooth gear 166 on the satellite meshes with a 72-tooth internal gear 167 of ring gear 161. An external 84-tooth gear 168 of ring gear 161, meshes with the 40-tooth gears 139 of sleeves 136. Sleeves 136 rotate plungers 90 through the interengagement of slots 141 and driving lugs 100.

As previously described, groove 94 of plunger 90 forms the spill or by-pass port and the opening thereof is controlled by porting sleeve 170. This control sleeve has the same close sliding fit with plunger 90 as the latter has in bore 50 of bushing 44. During the inward or delivery stroke of plunger 90, the intake port, represented by groove 93, closes when the outer edge 298 of groove 93 reaches edge 51 of bushing 44. As bushing 44 is non-adjustable, the point when the inlet port closes does not change during the operation of the pump. Therefore, the timing of the inlet port closing and thus the beginning of the injection is fixed with respect to the plunger motion and the angular rotation of the pump driving shaft.

Groove 94 is covered by sleeve 170 during the

injection period, when plunger 90 is delivering the fuel to the engine cylinder after closing of inlet port 93. At a point during the inward movement of the plunger, the inner edge 298 of groove 94 reaches edge 171 of sleeve 170. This opens the spill port, relieving all pressure in compression space 52 and ending the injection.

All of the control sleeves 170 are held in adjusted position by a control member 185 operated by the central capacity control mechanism of the pump. When sleeves 170 are moved by member 185 toward mounting flange 38 the point where the spill port opens is retarded. This lengthens the fuel delivery period, increasing the volume of the injection. It should be noted that the timing of the ending of the injection period is variable with the pump output, whereas the timing of the beginning of the injection period is fixed.

The delivery from each plunger should not vary by more than 1% from that from any other plunger. This requires extreme accuracy in the adjustment in the length of injection, which accuracy is not obtainable even by extremely accurate machining of the moving parts. Accordingly, an individual primary adjustment is provided for the exact point of the plunger stroke for each sleeve 170 where edge 298 of plunger groove 94 is aligned with edge 171 of sleeve 170.

Such adjustment is provided by threading sleeve 170 into an outer or adjustment sleeve 172. Sleeve 172 is fixed against longitudinal movement relative to central control member 185. Screwing sleeve 170 into sleeve 172 changes the position of edge 171 with respect to sleeve 172, thus adjusting the exact point during the plunger stroke when spill port 94 opens.

Sleeve 170 has a threaded portion 272 and a circular flange 173 in which are cut an even number of equally spaced notches 174. For example, there may be ten notches 174. Sleeve 172 has an enlarged part 176 at one end aligned with flange 173. A groove is cut around the outer surface of part 176 and an odd number of equally spaced holes 178 are drilled through the bottom of this groove. Holes 178 may be eleven in number, for example. These holes receive the hooked end 178 of ring 177, which engages one of the notches 174 to secure sleeves 170 and 172 against relative rotation. Wrinkle spring 180 is biased between flange 173 and the bottom of the recess in sleeve 172 to avoid any longitudinal motion of the sleeve due to play in the threads.

The use of a different number of notches and holes constitutes a vernier arrangement which permits an extremely close adjustment of sleeves 170 and 172. Sleeve 172 is formed with a pair of spaced annular ribs 181, 182 defining a groove 183. As shown in Figs. 1 and 10, this groove receives control member 185.

Control member 185 is slidably mounted on extension of sleeve 145 and held against rotation by a key 186. Member 185 has a sleeve portion formed with a helical spline, or a coarse "Acme" type thread 189. Intermediate the ends of member 185 is a circular flange 293 in which are cut notches 187 each engaging the groove 183 of a sleeve 172. Between each notch is a radial arm 188 extending into each groove 183.

Spline or thread 189 of member 185 engages mating spline or a thread on another sleeve 190 carrying a gear 191. Sleeve 190 is held against axial movement by a collar 192 having an edge resting against the inner face of gear 191. Screws 194 secure collar 192 tightly to diaphragm 38.

Collar 192 has a slot 193 through which gear 191 meshes with an idler gear 195 mounted on one of the bushings or sleeves 135 (Figs. 2 and 10). A snap ring 196 holds gear 195 in place.

As best seen in Figs. 10 and 11, idler gear 195 meshes with a sector gear 197 on the inner end of a control shaft 198. Shaft 198 is supported in housing 31 and a capacity control lever 199 is secured to its outer end. Movement of lever 199, through shaft 198, sector gear 197, and idler gear 195 effects rotation of gear 191 and sleeve 190. As control member 185 is non-rotatable, to key 186, and sleeve 190 is held against axial movement by collar 192, rotation of sleeve 190 effects axial movement of control member 185. Thus the positions of control sleeves 170 are all adjusted simultaneously.

Lubrication of the pump is effected in the following manner. Oil under pressure from the engine oil pump is delivered to a passage 201 in diaphragm 39. From there it enters an annular groove 202. Holes 203 in bushing 135 register with groove 202 and the oil may thus enter between sleeve 135 and sleeve 136 to lubricate these parts during relative rotation. Holes 204 allow oil to enter between sleeve 136 and plunger 90. A passage 205 connects groove 202 to an annular groove 206 in diaphragm 39. This groove is in communication with an axial passage 207 in pin 164, communicating with the inner bearing surface of satellite 163; furthermore, through a drilled passage (not shown), oil from annular groove 206 reaches the bearing surface of sleeve 146 receiving ring gear 161. Thus, oil under pressure is supplied to these several parts for lubrication.

Leakage from between satellite 163 and its pin 164 allows oil to enter the main part of drive compartment sections 32 and 33, to reach the other relatively moving surfaces. Lubrication of roller 108 and its bearing 109 is effected through an axial passage 208 in pin 110 having radial passages extending therefrom to an annular groove 209 in communication, through other radial passages 210 with the inner surface of roller 108.

Through a passage (not shown) drilled longitudinally through the wall of housing 31, oil under pressure reaches an annular groove 225 formed by a chamfer on housing 31. Nine equi-spaced passages 226 drilled radially in tappet housing 40 each connect groove 225 to one of nine annular grooves 227, each formed in one of the tappet receiving apertures in housing 40. A longitudinal groove 228 is cut in each aperture, intersecting annular groove 227. Grooves 228 are sufficiently long to remain in communication with axial passages 208 in pins 110 throughout the entire strokes of the tappets. The oil returns to the engine sump through suitable conduits or passages not shown in the drawing.

In the operation of the pump, fuel at a pressure of from four to twelve pounds is delivered from a transfer pump to inlet 38 where it enters fuel compartment 31. The fuel fills compartment 31, expelling vapor therefrom through the following arrangement. At the upper end of housing section 31, a cap member 215 is provided enclosing a vapor discharge space. Referring more particularly to Figs. 1 and 10, a valve 216 controls the flow of vapor from compartment 31 through a passage 211 to an outlet passage 318 from which it may be conducted outside the engine or its enclosure by a suitable conduit or the like. Valve 216 is reciprocable

by a lever 218 through the medium of a pin 219. Lever 218 is pivoted in section 31 at 220 and has at one end a float 221. At its opposite end, lever 218 is provided with a machined flat 222 resting against a shoulder 223 in the lower position of float 221. This maintains float 221 slightly spaced from a shoulder 224.

In the position of the float shown in Fig. 10, valve 216 is open permitting vapor to be discharged through passages 217, 218 as the fuel level rises in compartment 31. When the fuel reaches float 221, it lifts the latter closing valve 216 and thus sealing the outlet of chamber 31.

With fuel compartment 31 filled, fuel is delivered from the compartment by the several pumping units. This operation will best be understood by reference to Figs. 19 through 23.

Referring first to Figs. 14, and 19, plunger 90 is illustrated at the end of the suction or intake stroke, and ready to begin its inward or working stroke. The fuel has filled the interior of plunger 90 and compression space 52 during the preceding outward or suction stroke. It will be noted that, at the beginning of the inward stroke of plunger 90, compression space 52 is still in communication with fuel compartment 31 through inlet port 93.

Figs. 15 and 20 show the position of the plunger at the beginning of fuel injection. It will be noted that plunger 90 has rotated clockwise from the position of Figs. 14 and 19, as viewed in Fig. 20, and that longitudinal grooves 92 are now fully registered with bushing ports 59. At the same time, the plunger has moved inwardly so that the outer edge 295 of inlet groove 93 is aligned with lower edge 51 of plunger 44. Communication is thus cut off between compartment 31 and compression space 52. The plunger continues to move inwardly, and the fuel in compression space 52 is compressed and forced out through aperture 53 into channel 54. From channel 54, the fuel passes through aperture 63 into passage 67. The pressure of the fuel lifts check or delivery valve 72 and the fuel flows through cross-passage 70 into passage 68. From here, the fuel passes through aperture 64 into channel 55. Apertures 58 of bushing 44 permit passage of the fuel to groove or fuel chamber 91 which is in communication with grooves 92.

Grooves 92 deliver the fuel to bushing apertures 59 from which the fuel passes to grooves 60 and thus to channel 56. From channel 56, the fuel is delivered to sleeve aperture 65 into channels connecting this aperture to the engine cylinder spray nozzle as previously described.

The ending of the period of injection is shown in Figs. 16 and 21, wherein grooves 92 are still in full registry with apertures 59, plunger 90 having rotated clockwise from the position of Fig. 20. The upper edge 296 of spill channel 94 is aligned with the edge 171 of control sleeve 170. During the movement of the plunger as previously described, the spill port has been closed by control sleeve 170, maintaining a sealed compression space within the pumping unit.

The plunger continues to advance to the position shown in Figs. 17 and 22, which represent the ending of the compression stroke. In this latter position, the plunger has rotated further in a clockwise direction, but grooves 92 are still aligned with ports 59. However, the inward movement of the plunger has caused spill port 94 to be uncovered by control sleeve 170 and thus the interior of the plunger is now at the pressure

15

of fuel compartment 31 and the delivery of fuel to ports 58 has ceased.

From the position shown in Fig. 17, when the plunger has reached to center, plunger 90 begins its outward or suction stroke. Check valve 12 is closed, and some fuel enters plunger 90 through spill port 84 until this port is closed by sleeve 178 during outward movement of plunger 90. As the plunger continues to move outwardly with ports 93 and 84 closed, a partial vacuum is created in space 52 and channel 56 until intake port 83 opens. Fuel, under the combined action of such vacuum and, the pressure in compartment 31, rushes through port 83 filling all the space in bushing 44.

After the plunger reaches bottom center and begins its next inward stroke, intake port 83 is still open and fuel still enters the pumping unit. Once the bushing and plunger spaces are filled, plunger 90 starts to displace the fuel. Part of the fuel, and any vapor present, are expelled. Only "solid" fuel remains in the pumping unit after inlet port 83 closes as shown in Fig. 18. During its outward and the following partial inward movement, plunger 90 has continued to rotate clockwise and grooves 92 are thus brought into registry with bushing ports 61.

Figs. 18 and 23 show the pumping unit at the beginning of the injection period for ports 61. Grooves 92 are fully registered with ports 61 and the outer edge 295 of inlet channel 83 is sealed by the lower edge 51 of bushing 44. The fuel is compressed and delivered in the same manner as previously described from compression space 52 past valve 12 into grooves 92. Grooves 92 deliver the fuel to ports 61 which are connected by longitudinal grooves 62 which connect with annular channel 57. The fuel is delivered from channel 57 through sleeve ports 66 into the passages leading to another engine cylinder. Thus, on alternate strokes, plunger 90 distributes fuel to ports 58 and 61, respectively.

As stated, the plunger is designed to discharge fuel simultaneously in diametrically opposite directions to neutralize the hydraulic thrust on the plunger. This is best shown by diagrammatic representations in Figs. 24 and 25. Fig. 24 corresponds to the position of the plunger shown in Figs. 15 and 20. Diametrically opposite grooves 92 are registered with diametrically opposite ports 58 in bushing 44. Ports 58 deliver the fuel through passages 230, 238 to a single passage 231 which may represent port 65 of sleeve 45.

Fig. 25 corresponds to Figs. 18 and 23. Grooves 92 are now registered with apertures 61 which deliver fuel simultaneously to passages 232, 237 to a single passage 233 which corresponds to sleeve port 66. Thus, the fuel is delivered in opposite directions at the same time whereby the hydraulic side thrust on plunger 90 is neutralized.

The described pump comprises a novel and efficient unit for delivering fuel under pressure to a number of engine cylinders with not more than one half the number of pumping units hitherto thought necessary. The rotating plunger acts as a fuel distributor to alternate cylinders on alternate injection strokes. The timing of the injection is controlled independently of the plunger rotation by means cooperable with the reciprocating motion of the plunger. Furthermore, a novel and efficient plunger driving mechanism is provided as well as effective sealing means between the fuel and driving compartments. The pump is so constructed that it may be readily dis-

16

mantled for inspection or repair, either as a whole or as sub-units.

While a specific embodiment of the invention has been shown and described in detail to illustrate the application of the principle thereof, it should be understood that the invention may be otherwise embodied without departing from such principles.

What is claimed is:

1. In a fuel injection pump, passage means for delivering fuel under pressure to an engine; a pumping unit including a cylinder and a plunger coating therewith, said cylinder having diametrically opposed ports in communication with said passage means and a compression space beyond said plunger; said plunger having an annular fuel chamber in its outer surface and a pair of diametrically opposite longitudinal grooves communicating therewith and arranged to register simultaneously with a pair of said cylinder fuel receiving ports; passage means interconnecting said compression space and said fuel chamber; means effective to reciprocate said plunger and to rotate the same relatively to said cylinder, both in a predetermined relation to the engine crank shaft speed and to the relative angular position of the engine cranks, to inject fuel under pressure into said passage means; and adjustable means effective to regulate the amount of fuel delivered during each stroke of said plunger.
2. In a fuel injection pump, a pumping unit including a cylinder and a plunger coating therewith, the inner ends of said cylinder and plunger cooperating to form a compression space; said cylinder having two pairs of diametrically opposite ports; first passage means communicating with said ports to deliver fuel under pressure to an engine; said plunger being formed with a fuel chamber comprising an annular groove in its external surface and a pair of diametrically opposite grooves intersecting said chamber and selectively registerable with either pair of said cylinder ports; second passage means effective to deliver fuel from said compression space to said fuel chamber; and means operable to reciprocate said plunger and rotate the same relative to said cylinder to deliver fuel under pressure alternately to each pair of diametrically opposite cylinder ports.
3. In a fuel injection pump, a pumping unit including a cylinder and a plunger coating therewith, the inner ends of said cylinder and plunger cooperating to form a compression space; said cylinder having two pairs of diametrically opposite ports; first passage means communicating with said ports to deliver fuel under pressure to an engine; said plunger being formed with a fuel chamber comprising an annular groove in its external surface and a pair of diametrically opposite grooves intersecting said chamber and selectively registerable with either pair of said cylinder ports; second passage means effective to deliver fuel from said compression space to said fuel chamber; means operable to reciprocate said plunger and rotate the same relative to said cylinder to deliver fuel under pressure alternately to each pair of diametrically opposite cylinder ports; and a check valve in said second passage means effective to prevent flow of fuel from said fuel chamber to said compression space.
4. In a fuel injection pump, a pumping unit comprising, in combination, a cylinder, a plunger reciprocable and rotatable relatively to said cylinder and two different passage means arranged

to conduct fuel under pressure to an engine, said cylinder and plunger cooperating to form a compression space; said cylinder having a thick wall with fuel passages formed therethrough and first and second pairs of annular grooves and first and second pairs of diametrically opposite longitudinal grooves formed in its outer surface, each pair of longitudinal grooves intersecting one of said first pair of annular grooves; a thin-walled sleeve assembled over said cylinder and having a first pair of apertures each registering with one of said passage means and with one of said first pair of annular grooves, and a second pair of apertures each registering with one of said second pair of annular grooves; said plunger having an external annular groove forming a fuel chamber and a pair of diametrically opposite longitudinal grooves extending therefrom and forming distributing means; certain of said cylinder fuel passages registering with said second pair of cylinder annular grooves to interconnect said compression space and said fuel chamber; the other fuel passages being arranged as two pairs of diametrically opposed fuel ports, each port registering with one of said cylinder longitudinal grooves and also registrable with one of said distributing means; whereby rotation of said plunger will distribute fuel alternately to said passage means.

5. A fuel injection pump comprising, in combination, a fuel compartment; a drive compartment; partition means separating said compartments; a pump drive shaft; a plurality of pumping units, each comprising a cylinder mounted in said fuel compartment and a rotating plunger coacting with said cylinder; a plurality of sleeves extending through said partition means, each of said plungers extending through one of said sleeves into said driving compartment; said plungers being reciprocable through said sleeves but being fixed against rotation relative thereto; first sealing means between said plungers and said sleeves; second sealing means between said partition means and said sleeves; a pair of passage means for delivering fuel under pressure to an engine from each of said pumping units; each cylinder having two pairs of diametrically opposed ports, each pair of ports connecting with one of said passage means; impulsing means in said drive compartment operable at a rate proportional to the engine crank shaft speed to successively reciprocate said plungers to inject fuel under pressure into a passage means; said mechanism operable by said pump drive shaft to rotate said sleeves and their associated plungers to deliver fuel alternately to each pair of diametrically opposed ports of each cylinder during alternate strokes of said plungers.

6. A fuel injection pump comprising, in combination, a fuel compartment; a drive compartment; partition means separating said compartments; a pump drive shaft; a plurality of pumping units, each comprising a cylinder mounted in said fuel compartment and a rotating plunger coacting with said cylinder, said units being equi-spaced and parallel with the pump shaft; a plurality of sleeves extending through said partition means, each of said plungers extending through one of said sleeves into said driving compartment; said plungers being reciprocable through said sleeves but being fixed against rotation relative thereto; first sealing means between said plungers and said sleeves; second sealing means between said partition means and said sleeves; a pair of passage means for delivering fuel under pressure to an engine.

pressure to an engine from each of said pumping units; each cylinder having two pairs of diametrically opposed ports, each pair of ports connecting with one of said passage means; a tappet connected with the end of each plunger in the drive compartment; a roller mounted on each tappet; a shaft rotatably mounted in said drive compartment and having a circular face cam formed with a lobed skirt engaging said rollers to reciprocate said plungers successively to inject fuel under pressure into said passage means; mechanism operable by said shaft to rotate said sleeves and their associated plungers to deliver fuel alternately to the spaced ports of each cylinder during alternate strokes of said plungers; and a driving connection between said shaft and the engine.

7. A fuel injection pump comprising, in combination, a fuel compartment; a drive compartment; partition means separating said compartments; a pump drive shaft; a plurality of pumping units, each comprising a cylinder mounted in said fuel compartment and a rotating plunger coacting with said cylinder, said units being equi-spaced and parallel with the pump shaft; a plurality of sleeves extending through said partition means, each of said plungers extending through one of said sleeves into said driving compartment; said plungers being reciprocable through said sleeves but being fixed against rotation relative thereto; first sealing means between said plungers and said sleeves; second sealing means between said partition means and said sleeves; a pair of passage means for delivering fuel under pressure to an engine from each of said pumping units; each cylinder having two pairs of diametrically opposed ports, each pair of ports connecting with one of said passage means; a tappet connected with the end of each plunger in the drive compartment; a roller mounted on each tappet; a shaft rotatably mounted in said drive compartment and having a circular face cam formed with a lobed skirt engaging said rollers to reciprocate said plungers successively to inject fuel under pressure into said passage means; and gearing connecting said shaft and said sleeves to rotate the associated plungers to deliver fuel alternately to each pair of spaced ports of each cylinder during alternate strokes of said plungers.

8. In a fuel injection pump, a pair of passage means for delivering fuel under pressure to an engine; a pumping unit including a cylinder and a plunger coacting therewith, said cylinder having a first pair of diametrically opposite ports both communicating with one passage means, and a second pair of diametrically opposite ports both communicating with the other passage means; said first pair of ports being spaced ninety degrees from said second pair; said plunger having a fuel chamber and a pair of diametrically opposite fuel passages communicating with said chamber and arranged to register simultaneously with both ports of one of said pairs of cylinder ports, whereby said plunger is hydraulically balanced to eliminate binding thereof in said cylinder during discharge of fuel under pressure to said passage means; impulsing means operable in a predetermined relation to the engine crank shaft speed to reciprocate said plunger to inject fuel under pressure into a passage means; and mechanism operable by said impulsing means to rotate said plunger ninety degrees during each stroke to deliver fuel under pressure alternately to said passage means.

9. A fuel injection pump comprising, in com-

bination, a drive shaft; a plurality of pumping units, each including a cylinder and a plunger coacting therewith, said units being equi-spaced and parallel to said shaft; a plurality of pairs of passage means, each pair being operative to deliver fuel under pressure from one of said units to the engine; each cylinder having a first pair of diametrically opposite ports both communicating with one passage means of the pair associated with its respective pumping unit and a second pair of diametrically opposite ports both communicating with the other passage means of the pair associated with its respective pumping unit; said first pair of ports being spaced ninety degrees from said second pair; each plunger having a fuel chamber and a pair of diametrically opposite fuel passages communicating with said chamber and arranged to register simultaneously with both ports of one of said pairs of cylinder ports, whereby said plunger is hydraulically balanced to eliminate binding thereof in said cylinder during discharge of fuel under pressure to said passage means; a cam rotatable by said shaft in a plane perpendicular thereto and having impulsing means effective to reciprocate said plungers successively to deliver fuel under pressure to said passage means; and mechanism operable by said cam to rotate each plunger during each stroke to deliver fuel under pressure alternately to its associated passage means; the angular velocity of said plungers being equal to one-fourth of the angular velocity of said cam multiplied by the cam impulses per plunger per cam revolution.

10. A fuel injection pump comprising, in combination, pairs of passage means for delivering fuel under pressure to an engine; a plurality of pumping units each associated with one of said pairs of passage means and each including a cylinder and a plunger coacting therewith, each cylinder having a first pair of diametrically opposite ports both communicating with one of its associated passage means, and a second pair of diametrically opposite ports both communicating with the other of its associated passage means; a fuel reservoir; each plunger cooperating with its cylinder to form a compression space and having a fuel chamber communicable with said compression space and a pair of diametrically opposite fuel passages communicating with said chamber and arranged to register simultaneously with both ports of one of said pairs of cylinder ports, whereby the plunger is hydraulically balanced to eliminate binding thereof in its cylinder during discharge of fuel under pressure to its associated passage means; each plunger extending into said fuel reservoir and having an inlet port and a spill port spaced longitudinally from each other arranged to connect its compression space to said reservoir; impulsing means operable by a drive shaft in a predetermined relation to the engine crank shaft speed to reciprocate said plungers to inject fuel under pressure into the passage means; mechanism operable by said impulsing means to rotate said plungers ninety degrees during each stroke to deliver fuel under pressure alternately to the associated passage means of each pumping unit; said plunger fuel passages having a greater circumferential length than that of said cylinder ports; and control sleeves in said reservoir each adjustable longitudinally of a plunger relative to its spill port to adjust the length of the fuel injection period independently of the rotation speed of the plunger.

er; whereby the relative circumferential dimensions of said plunger fuel passages and said cylinder ports are not critical.

11. A fuel injection pump comprising, in combination, pairs of passage means for delivering fuel under pressure to an engine; a plurality of pumping units each associated with one of said pairs of passage means and each including a cylinder and a plunger coacting therewith, each cylinder having a first pair of diametrically opposite ports both communicating with one of its associated passage means, and a second pair of diametrically opposite ports both communicating with the other of its associated passage means; a fuel reservoir; each plunger cooperating with its cylinder to form a compression space and having a fuel chamber communicable with said compression space and a pair of diametrically opposite fuel passages communicating with said chamber and arranged to register simultaneously with both ports of one of said pairs of cylinder ports, whereby the plunger is hydraulically balanced to eliminate binding thereof in its cylinder during discharge of fuel under pressure to its associated passage means; each plunger extending into said fuel reservoir and having an inlet port and a spill port spaced longitudinally from each other arranged to connect its compression space to said reservoir; impulsing means operable by a drive shaft in a predetermined relation to the engine crank shaft speed to reciprocate said plungers to inject fuel under pressure into the passage means; mechanism operable by said impulsing means to rotate said plungers ninety degrees during each stroke to deliver fuel under pressure alternately to the associated passage means of each pumping unit; control sleeves in said reservoir each adjustable longitudinally of a plunger relative to its spill port to adjust the length of the fuel injection period independently of the rotation speed of the plunger; a disk mounted coaxially with the drive shaft and including means engaging all the plunger control sleeves simultaneously; mechanism for shifting said disk axially to adjust the pump output; and means for individually adjusting each of said control sleeves with respect to said disk to equalize the outputs of the respective pumping units.
